PROCESS FOR THE TREATMENT OF OLEFINIC SULPHUR-BEARING GASOLINE TO EFFECT SUBSTANTIAL DESULPHURIZATION AND REFINING

Robert M. Cole, Oakland, Calif., assignor to Shell Development Company, San Francisco, Calif., a corporation of Delaware

Application February 10, 1945, Serial No. 577,181

5 Claims. (Cl. 196—24)

This invention relates to the treatment of thermally cracked gasolines, catalytically cracked gasolines, thermally reformed gasolines, and similar materials of the gasoline boiling range containing substantial amounts of olefins and/or other unsaturated bodies and other impurities such as sulphur compounds, nitrogen compounds, etc., to effect a substantial desulphurization and to remove and render innocuous various gum-forming bodies. More particularly the invention relates to the treatment of such materials by the combined action of hydrogen and catalysts under such conditions and in such a manner as to afford the desired finishing or refining treatment with a minimum loss of material, minimum consumption of hydrogen, and with substantially no depreciation of the anti-knock characteristics.

Gasolines produced by thermal cracking, gasolines produced by catalytic cracking, and gasolines produced by thermal reforming of various gasoline stocks usually have the following characteristics: They contain appreciable quantities of olefins and other unsaturated bodies and consequently have a high bromine number and high acid heat. They contain appreciable amounts of sulphur compounds, nitrogen compounds, etc. They have poor color stability, poor gum stability, and poor lead susceptibility. Consequently these stocks generally require some sort of finishing treatment to make them acceptable for use in gasoline of present-day quality. The conventional method of finishing these materials is the conventional sulphuric acid treatment followed by a doctor treatment and rerunning. This method has the recognized disadvantages of incomplete sulphur removal, high acid consumption, poor yields, and an appreciable depreciation of anti-knock properties. In view of these disadvantages considerable attention has been given to the finishing of such materials by catalytic hydrogenation. Certain such processes have been proposed. However, the proposed processes have certain disadvantages and furthermore are usually too costly to make their use economical except in the special case of the production of substantially saturated blending materials for premium grade aviation gasoline.

The present process provides a means for effecting excellent desulphurization and refining while affording a product of excellent anti-knock characteristics. These desirable results are obtained with a low consumption of hydrogen and with excellent catalyst life. Consequently the process of the invention is also applicable and

particularly advantageous for the catalytic finishing of motor gasolines of substantially full boiling range and similar non-premium products.

The sulphur compounds in gasolines of the type described are largely thiophenic sulphur compounds. These compounds are quite aromatic in character and are exceedingly difficult to remove except by relatively drastic hydrogenation. The loss of octane number usually encountered in the catalytic desulphurization by hydrogenation of olefinic gasolines of the type described is due largely to the fact that these relatively drastic hydrogenation conditions are required. Thus, when effecting the hydrogenation in the usual manner to the extent necessary to effect a satisfactory removal of sulphur an appreciable amount of the aromatic hydrocarbon constituents of the gasoline is hydrogenated to naphthenic hydrocarbons of relatively low anti-knock value. Also, at least a large part of the normal olefins which have good anti-knock properties are hydrogenated to the corresponding normal paraffin hydrocarbons having very poor anti-knock properties. These undesired hydrogenations are not only particularly detrimental in decreasing the anti-knock properties of the gasoline, but also account for a large part of the hydrogen consumption.

In my co-pending application, Serial No. 30 568,843, filed December 19, 1944, of which this application is a continuation-in-part, I have shown that the various normal constituents of such gasolines differ somewhat in their susceptibilities toward hydrogenation. I have 35 shown that when treating aromatic fractions such as toluene, the hydrogenation of the toluene may be prevented while allowing the hydrogenation of thiophenic sulphur compounds to be carried substantially to completion by maintaining 40 a small concentration of olefins in the hydrogenation reaction zone. For this purpose, small amounts of olefins are added, preferably at points along the length of the reaction zone. A similar principle may be applied also to prevent to a certain extent the undesired hydrogenation of normal olefins. The process of the present invention makes use of both of the above principles for 45 the catalytic treatment of cracked gasolines and similar olefinic materials of the type described and allows such materials to be substantially desulphurized and hydrofined with minimum consumption of hydrogen and without loss of anti-knock properties.

The process of the present invention in its 50 broader and more general aspect comprises treat-

ing the olefinic gasoline in the presence of a fraction of the partially treated product, obtained as later specified, with hydrogen in the presence of a sulph-active hydrogenation catalyst under suitable conditions, separating the product into a plurality of fractions having different boiling ranges, withdrawing the lowest boiling fraction and blending it with a portion of the higher boiling material, and recycling at least a portion of the higher boiling material to the hydrogenation zone, the through put rate and recycle ratio being adjusted to provide the desired quality of the blend withdrawn.

The process will be described in more particular in connection with the description of a typical operation. To assist in this description reference is had to the attached drawing wherein there is shown by means of conventional figures, not drawn to scale, a suitable assembly of conventional apparatus arranged and adapted for operation according to the process of the invention. Referring to the drawing the olefinic gasoline, which may be any gasoline of the type described and may boil from about 100° F. up to about 425° F. or within this range, is introduced via line 1 and pump 2. This gasoline, which for the purpose of illustration may be considered to be a debutanized catalytically cracked gasoline boiling up to about 360° F., is mixed with an appropriate amount of heavy gasoline, obtained as hereinafter specified, entering via line 3. The mixture is preheated in coil 4 of furnace 5. Recycled gas rich in hydrogen is simultaneously preheated in coil 6 of furnace 5 and is mixed with the hydrocarbon feed. The mixture at about the desired reactor inlet temperature passes via line 7 to a catalytic converter or reactor 8 provided with a sulph-active hydrogenation catalyst. The catalyst in reactor 8 may be any of the known conventional sulph-active hydrogenation catalysts. Suitable catalysts, by way of example, are tungsten sulphide-nickel sulphide, cobalt sulphide, molybdenum sulphide, cobalt thiomolybdate, iron sulphide, molybdenum oxide and the various composites thereof which, furthermore, may or may not contain such materials as alumina, magnesia, silica, zinc oxide, chromium oxide, etc., as stabilizers, promoters, or supports. The temperature in reactor 8 is maintained below about 950° F., and is usually above about 400° F. Thus, typical temperatures are, for example, between about 450° F. and 850° F. The pressure is usually in the order of 200-1000 p. s. i. The mol ratio of hydrogen to hydrocarbon in the feed to the reaction zone is preferably between about 2 and 30.

The treated product leaves the reactor 8 via line 9 and cooler 11 and passes to a separator 10. Gas rich in hydrogen is removed from the upper part of separator 10. This gas is usually subjected to one or more compression and cooling steps to separate condensable hydrocarbons and is then usually cycled through a hydrogen sulphide removal system, such as a Shell phosphate system, to remove hydrogen sulphide formed in reactor 8. These refinements form no part of the invention, are well understood in the art, and are consequently not shown in the drawing. The hydrogen gas is recycled to the heater via line 12. Hydrogen for the process is supplied via line 13.

The liquid product from separator 10 is withdrawn via line 14 and passed to a fractionating tower 15 wherein it is separated into a lower boiling fraction and a higher boiling fraction,

5 The higher boiling fraction is withdrawn in part via line 16 to a second fractionating tower 17 wherein it is again separated into a lower boiling fraction and a higher boiling fraction. The higher boiling fraction from fractionator 17 is withdrawn in part via line 18 to a third fractionating tower 19 wherein it is again separated into a lower boiling fraction and a higher boiling fraction. The higher boiling fraction is withdrawn via line 20. Part of it is recycled as hereinafter specified and the remainder is withdrawn via line 25. The lower boiling fractions from the three fractionating towers are withdrawn via lines 22, 23 and 24 to line 25. This mixture is combined with a portion of the higher boiling fraction from line 20 and the blend, now corresponding approximately in boiling curve to the original feed, passes to a caustic scrubber 27 to remove dissolved hydrogen sulphide. The treated product is withdrawn via line 28. A substantial part of the higher boiling fractions from the respective fractionators is withdrawn via lines 29, 30 and 20 and recycled via line 21, pump 32 and line 3. This blend is the heavy gasoline referred to above.

20 The cut points between the various fractions are not critical and may be made at any convenient points. In general, however, the end point of the first or lowest boiling fraction withdrawn via line 22 is in the order of 180° F.-225° F. Thus, for instance, the initial boiling points of the three heavy fractions in the operation described above may be 200° F., 250° F., and 300° F., respectively.

25 The composition and amount of the heavy gasoline recycled via line 21 depends upon the particular character of the feed and is preferably adjusted during operation to obtain the optimum results. In general, the amounts of the higher boiling fractions recycled are roughly proportional to their molecular weights or boiling points. Thus, in the described operation, by way of example, the heavy gasoline may consist of 40% of the heavy material withdrawn from fractionator 15, 50% of the heavy material withdrawn from fractionator 17, and 60% of the heavy material withdrawn from fractionator 19. Since the heavy fraction from fractionator 15 contains considerable amounts of the same components as found in the heavy fractions from fractionators 17 and 19 it is seen that the concentration of heavy materials is greatest in the higher boiling range. Likewise, the treatment afforded the product is approximately inversely proportional to the molecular weight or boiling range. For example, the material withdrawn via line 22 may have been treated at an effective liquid hourly space velocity of 15; that withdrawn via line 23 may have been treated at an effective liquid hourly space velocity of 8; that withdrawn via line 24 may have been treated at an effective liquid hourly space velocity of 3; and the material withdrawn via line 20 may have been treated at an effective liquid hourly space velocity of 1.

30 35 40 45 50 55 60 65 70 75 While the process described above for purposes of illustration involves three separate fractionation steps and consequently involves six separate hydrocarbon fractions it will be appreciated that the principle of the invention may be applied with two or even one distillation steps or a single fractionation column adjusted and designed to afford a lower boiling overhead product, a heavy bottom product, and one or more intermediate side streams may be employed. For example, a gasoline boiling essentially between

100° F. and 380° F. may be treated and the products separated into three fractions boiling, for instance, between 100° F.-200° F., 200° F.-300° F., 300° F.-380° F., respectively. The lower boiling, or 100° F.-200° F., fraction of the product may be withdrawn and blended with appropriate amounts of the two heavier fractions, and portions of the 200° F.-300° F. fraction and the 300° F.-380° F. fraction may be recycled in such amounts to afford the desired results. Thus, when treating a thermally cracked gasoline as described, the liquid hourly space velocity may be adjusted, for example, so that the 100° F.-200° F. fraction has the following properties:

	100° F.-200° F. fraction	
	Of the product	Of the feed
Percent sulphur.....	0.2	0.4
Bromine number.....	75	95
ASTM octane number (1 cc. TEL).....	77.2	76.5

The properties of the corresponding fraction of the feed are given for comparison. The amount of 200° F.-300° F. fraction of the product blended with the feed and hence recycled may be adjusted to afford a product having, for instance, either of the two following sets of properties:

	200° F.-300° F. fraction		
	Of the product	Of the product	Of the feed
Percent sulphur.....	0.2	0.4	0.7
Bromine number.....	56	76	87
ASTM octane number (clear).....	69.1	70.7	70.4
ASTM octane number (1 cc. TEL).....	75	74.7	73.4

The treatment required for attaining these results in the hydrogenation process described above corresponds, for example, to an effective liquid hourly space velocity of about 20 at a temperature of about 550° F.-600° F., i. e. a liquid hourly space velocity affording a contact time equivalent to that in treating this fraction in the absence of other fractions in a single pass at a liquid hourly space velocity of 20. The amount of the 300° F.-380° F. fraction recycled may be adjusted to afford a product having, for instance, the following properties:

	300° F.-380° F. fraction	
	Of the product	Of the feed
Percent sulphur.....	0.01	1.1
Bromine number.....	2	50
ASTM octane number (1 cc. TEL).....	72.6	69.1

In order to obtain such results an effective liquid hourly space velocity between about 0.5 and 2 is generally required.

An object of the described operation is to subject in a single apparatus and in a most advantageous way the higher molecular weight and higher boiling constituents of the feed stock to a substantial and relatively thorough hydrogenation treatment approximately proportional to the molecular weight or boiling point to remove thiophenic sulphur compounds while at the same time subjecting the lower boiling components of

the feed to a very mild hydrogenation treatment, thereby to preserve the major part of the olefins in this portion of the feed and at the same time to utilize these lower boiling olefins to prevent hydrogenation of aromatic hydrocarbons in the more drastically treated higher boiling fraction of the feed. Expressed in another way, the olefinic constituents of the feed are hydrogenated in the present process approximately in proportion to their molecular weights or boiling points. Thus, the lowest boiling olefins, for instance those boiling below about 200° F., are hydrogenated only to a minor extent, for instance 25% or less, and the highest boiling olefins, for instance in the heaviest 50° F. boiling range portions of the olefinic gasoline, are substantially hydrogenated; for instance, 75% or more. It will be noted that in the present process the feed and product have essentially the same boiling curve as measured, for example, by an ASTM distillation, whereas the boiling curve of the combined feed to reactor 8 is concentrated in higher boiling constituents. The above objects cannot be obtained either by separating the feed initially into separate fractions and treating each fraction separately or by treating the whole fraction under different conditions adapted to effect the desired hydrogenation of the higher boiling olefins. The first method does not afford the desired protection of the high anti-knock aromatic hydrocarbons by the lower boiling olefins and the second method produces excessive saturation of lower boiling olefins and loss in anti-knock properties.

I claim as my invention:

1. A process for the treatment of olefinic sulphur-bearing gasoline to effect a substantial desulphurization and refining thereof which comprises adding to said gasoline a portion of heavy gasoline obtained as hereinafter specified, subjecting the mixture to the action of a mol excess of hydrogen in the presence of a sulph-active hydrogenation catalyst at a temperature between about 400° F. and 950° F. and under superatmospheric pressure and at a space velocity adjusted to give hydrogenation of only a part of the lowest boiling olefins, separating the product of said treatment into a plurality of fractions of different boiling ranges, reblanding the lowest boiling fraction with amounts of the higher boiling material sufficient to produce a blend having essentially the ASTM distillation curve of the untreated gasoline and recycling a second substantial portion of the higher boiling material as the heavy gasoline specified above.

2. A process for the treatment of olefinic sulphur-bearing gasoline to effect a substantial desulphurization and refining thereof which comprises adding to said gasoline a portion of heavy gasoline obtained as hereinafter specified, subjecting the mixture to the action of a mol excess of hydrogen in the presence of a sulph-active hydrogenation catalyst at a temperature between about 400° F. and 950° F. and under superatmospheric pressure, separating the product of said treatment into a plurality of fractions of different boiling ranges, reblanding the lowest boiling fraction with amounts of the higher boiling material sufficient to produce a blend having essentially the ASTM distillation curve of the untreated gasoline and recycling a second substantial portion of the higher boiling material as the heavy gasoline specified above, the relative proportions of said sulphur-bearing gasoline feed and said heavy gasoline being adjusted to afford a

substantial hydrogenation of olefins in said heavy gasoline and only a minor hydrogenation of the lower boiling olefins.

3. A process for the treatment of olefinic sulphur-bearing gasoline to effect a substantial desulphurization and refining thereof which comprises adding to said gasoline a portion of heavy gasoline obtained as hereinafter specified, subjecting the mixture to the action of a mol excess of hydrogen in the presence of a sulph-active hydrogenation catalyst at a temperature between about 400° F. and 950° F. and under superatmospheric pressure and at a space velocity adjusted to give hydrogenation of only a minor part of the lowest boiling olefins, separating the product of said treatment into a plurality of fractions of different boiling ranges including a lower boiling olefinic fraction having an end point between about 180° F. and 225° F., reblending said lower boiling olefinic fraction with amounts of the higher boiling material sufficient to produce a blend having essentially the ASTM distillation curve of the untreated gasoline and recycling a second substantial portion of the higher boiling material as the heavy gasoline specified above, the amount of said higher boiling material recycled being such that the major portion of the

olefins of the heaviest 50° F. boiling range portion of said olefinic gasoline feed is hydrogenated.

4. Process according to claim 1 in which the hydrogenation treatment is carried out at a temperature between 450° F. and 850° F.

5. In a process for the treatment of olefinic sulphur-bearing gasoline to effect a substantial desulphurization and refining thereof by catalytic hydrogenation in the presence of a sulph-active hydrogenation catalyst at a temperature between about 400° F. and 950° F., the improvement which comprises charging to the treatment an olefinic sulphur-bearing gasoline, with drawing from said treatment a partially hydrogenated and substantially desulphurized gasoline having essentially the same ASTM distillation curve as the charge, and maintaining the concentration of higher boiling constituents of said gasoline in said hydrogenation treatment above the normal of said ASTM distillation curve by the internal recycle of a substantial portion of said higher boiling constituents whereby said higher boiling constituents are treated in the presence of lower boiling olefins at a lower effective liquid hourly space velocity than that of said lower boiling olefins.

ROBERT M. COLE.
